UNITED STATES PATENT OFFICE.

GEORGE H. FRETTS, OF SPRINGFIELD, MASSACHUSETTS.

ELECTRICALLY-OPERATED CONTROLLING MECHANISM.

No. 813,638.

Specification of Letters Patent.

Patented Feb. 27, 1908.

Application filed May 13, 1905. Serial No. 260,315.

To all whom it may concern:

Be it known that I, GEORGE H. FRETTS, a citizen of the United States, residing at Springfield, in the county of Hampden and State of Massachusetts, have invented new and useful Improvements in Electrically-Operable Controlling Mechanism, of which the following is a specification.

This invention relates to electrically-operable controlling mechanism capable of successful use in many connections. It is of prime advantage when employed in connection with a street-railway switch, and in the form of embodiment of the invention which I have selected for illustration in the drawings accompanying and forming a part of this specification, I represent the mechanism as associated with and adapted to operate a switch. In this particular adaptation of the invention it involves two solenoids adapted to be alternately energized and to swing the switch-tongue in opposite directions—that is to say, one solenoid when energized will through its connections with the switch-tongue move the latter in one direction, and when the other solenoid is energized it will move the switch-tongue in the opposite direction.

It is one of the objects of the invention to hold the solenoids in position in a solid substantial manner, so that they cannot be moved in any direction—that is, either upward or downward or sidewise.

A further object of the invention is in the provision of means for holding the cores of the respective solenoids fixedly in certain positions, by virtue of which the switch-tongue cannot move.

The invention includes other objects and advantages, which, with the foregoing, will be set forth at length in the following description, while what is novel in the invention will be included in the claims succeeding said description. In the latter I will set forth in detail the showing made by the drawings, but I wish to state at this point that I do not limit myself to the disclosure thus made, for certain variations may be adopted within the scope of my claims.

Referring to the drawings, Figure 1 is a sectional front elevation of a mechanism involving my invention. Fig. 2 is a transverse sectional view of the same. Fig. 3 is a detail view, upon an enlarged scale, of a part of a solenoid-core and certain coöperating devices. Fig. 4 is a top plan view of the same.

Like characters refer to like parts throughout the views.

The moving parts of the mechanism are, to protect them from the weather and injury and when used in connection with a railway-switch, housed within a casing, as 2, which may be conveniently made by casting and which is sunk in the road-bed of a railway adjacent a switch, the tongue of which I will denote by 3. The top or cover of the casing or box 2 is bolted or otherwise secured in place, some suitable form of packing being interposed between said top and the body of the box to secure a water-tight joint therebetween. Within the casing I have shown a rocker or lever 4, fulcrumed between its ends upon a bracket or bearing 5. The bracket or bearing has its working surface of V shape to receive the fulcrum of the lever, which is in the form of a knife-edge. Extending through a stuffing-box 6 in the upper side of the casing adjacent to the bed of the switch-tongue 3 is a rod 7, which is supported for endwise movement by the said switch-tongue bed and which is notched in its upper side to receive the tongue, so that as the rod is longitudinally moved the switch-tongue will be vibrated. The inner end of the rod 7 is connected by a swivel 8 with the rocker or lever 4 directly over the fulcrum thereof. Within the casing are two solenoids, each of which will be denoted in a general way by 9 and the coils of which are connected to wires or equivalent conductors extending into the casing through a laterally-extending tube 10. The bases of the solenoids rest upon a board 11, fitted closely within the casing and in circular holes formed in a second board superimposed upon the board 12 and also fitted snugly within the casing. The two boards 11 and 12 constitute a support for preventing downward and lateral motion of the two solenoids, the support having, as will be understood, a seat for said solenoids.

Clamped to the tops of the solenoids is a chemically-treated board 13, having holes through which the brass tubes forming part of and extending slightly above the windings of the two solenoids project. The board 13 has perforations near its opposite ends to receive the shanks of bolts 15, the lower hooked ends of which engage under lugs, as 16, upon the opposite sides of the casing interiorly thereof, so that when the nuts of said bolts are set up it will be evident that the bolts firmly press the clamping-board 13 against

the upper faces of the two solenoids, the three boards, as will be obvious, holding the solenoids in place in a firm substantial manner.

5 To the upper ends of the cores of the solenoids rods, as 17, are connected and are bifurcated at their upper ends to straddle or receive between their branches the outer ends of the rocker 4. The branches of the 10 two bifurcations are connected by knife-edges fitted against V-bearings on the upper side of the rocker near the opposite ends thereof.

It will be evident from the description 15 thus far made that when the solenoid on the right in Fig. 1 is energized its core will be attracted so as to throw the switch-tongue 3 to the right by reason of the intermediate connections. When the other solenoid is energized, the tongue will be oppositely moved.

The core of each solenoid 9 has a channel in its outer side extending downward therefrom a suitable distance from the upper edge thereof. Into each channel is set a latch, as 25 18, the hooks of the latches being adapted to engage catches, as 19, which may be integral with the casing, but the working portions of which, or those parts thereof which are engaged by the hooked ends of the latches, being covered with brass in order to assure the proper action of the latches. The latches 18 are pivoted in place, and for this purpose rivets may be used. The latches 18 are adapted 30 to alternately engage the catches or lugs 19 in order to hold the switch-tongue 3 firmly in a shifted position. Behind each latch 18 and in the channel in which it works I arrange a spring, as 20, the springs being preferably of brass. The springs insure the shouldered 35 portions of the latches snapping promptly over their catches or keepers, and as they are made of brass they prevent the iron latches from touching the respective cores, so that when the current is cut off from either solenoid 40 the latch associated therewith can be returned instantly to its operative position. It will be assumed that the latch 18 on the left engages its coöperating catch 19, the solenoid 9 on the right having been previously 45 energized to throw the switch-tongue 3 to the right. It will be assumed that it is desired to move the switch-tongue in the opposite direction, to accomplish which result it will be necessary to energize the solenoid 9 on the left. When said solenoid is energized, it will attract its core, and as the latter is magnetized it in turn, attracts the latch 18, 50 acting as an armature so as to carry the latch from off the catch, after which the solenoid-core on the left itself will be attracted by the solenoid in order to swing the switch-tongue from the right to the left. The initial operation, therefore, that takes place in any event 55 is the release of a latch and thereafter the 60 movement of the core carrying said latch.

Having thus described my invention, what I claim is—

1. The combination of a switch-tongue, a casing, a pair of solenoids in said casing, a rocker provided with a knife-edge fulcrum, a 70 V-shaped bearing in the casing for supporting said fulcrum, rods provided with knife-edges, the opposite branches of the rocker having V-shaped bearings to support said last-mentioned knife-edges, and the rods being connected with the cores of the respective solenoids, and operative connections between the rocker and the switch-tongue. 75

2. The combination of a casing, a board fitted in the casing, solenoids supported upon 80 the board, a second board fitted in the casing and resting upon the first board and having holes in which the bottoms of the solenoids fit, a third board fitted against the tops of the solenoids, the latter having tubes extending 85 upward therefrom and the third board having holes for the passage of the tubes, means for clamping the third board against the solenoids, a rocker fulcrumed between its ends in the casing, the opposite branches thereof 90 being operatively connected with the cores of the solenoids, a switch-tongue, and operative connections between the switch-tongue and the rocker.

3. A solenoid and its core, combined with 95 a latch carried by said core and arranged to be attracted by the core on the energization of said solenoid.

4. The combination of a solenoid and its core, a latch carried by the core and arranged 100 to be attracted by the core on the energization of the solenoid, and a brass spring between the latch and the core.

5. The combination of a solenoid and its core, the latter having a channel, and a latch 105 pivotally supported in the channel and arranged to be attracted by the core on the energization of the solenoid.

6. The combination of a pair of solenoids and their cores, latches carried by the cores 110 and arranged to be attracted thereby on the energization of the respective solenoids, and catches arranged to be alternately engaged by the latches.

7. The combination of a pair of solenoids 115 and their cores, latches carried by the cores and arranged to be attracted thereby on the energization of the respective solenoids, catches arranged to be alternately engaged by the latches, a switch-tongue, and connections between the solenoid-cores and switch-tongue for operating the latter.

In testimony whereof I have hereunto set my hand in presence of two subscribing witnesses.

GEORGE H. FRETTS.
